US00D981390S

(12) **United States Design Patent** (10) **Patent No.:** **US D981,390 S**
(45) **Date of Patent:** **** Mar. 21, 2023**

(54) **MOBILE PHONE HOLDER**

(71) Applicant: **SHENZHEN GEDUO NETWORK TECHNOLOGY CO., LTD.**, Shenzhen (CN)

(72) Inventor: **Huan Wu**, Wuxue (CN)

(73) Assignee: **SHENZHEN GEDUO NETWORK TECHNOLOGY CO., LTD.**, Shenzhen (CN)

(**) Term: **15 Years**

(21) Appl. No.: **29/823,592**

(22) Filed: **Jan. 18, 2022**

(51) LOC (14) Cl. **14-03**

(52) U.S. Cl.

USPC **D14/253**

(58) **Field of Classification Search**

USPC D14/217, 248, 250, 251, 252, 253, 432, D14/434, 440, 447, 457; D12/114, 223, D12/400, 407, 415, 425

CPC H04M 1/06; H04M 1/04; B60R 11/0241
